UNITED STATES PATENT OFFICE.

HUGO BORCHARDT, OF CHARLOTTENBURG, GERMANY.

TOGGLE-BREECH MECHANISM FOR AUTOMATIC FIREARMS.

1,090,515.

Specification of Letters Patent. Patented Mar. 17, 1914.

Application filed October 21, 1912. Serial No. 726,961.

To all whom it may concern:

Be it known that I, HUGO BORCHARDT, a citizen of the United States of America, residing at 31 Kantstrasse, Charlottenburg, in the Empire of Germany, have invented a certain new and useful Improvement in Toggle-Breech Mechanism for Automatic Firearms, of which the following is a specification.

10 The present invention has for its object an improvement in the toggle breech in accordance with U. S. Patent No. 918,951 in which a movable bearing or stop is arranged at one hinge of the toggle by means of 15 which stop the toggle is brought from its extended position under the influence of the bottom pressure of the cartridge, thereby opening the breech.

While in the breech in accordance with 20 U. S. Patent No. 918,951 a separate tappet arm of the breech block guided with clearance on one side serves as the movable toggle bearing acting on one of the arms of the toggle in accordance with the present invention 25 the wall of the casing is utilized for this purpose.

An embodiment of the invention is diagrammatically illustrated by way of example in the accompanying drawing.

30 Figure 1 is a side elevation of the breech, partly in section. Fig. 2 is a diagrammatic view showing the middle lines and the hinges of the toggle joint and in section the portion of the casing underlying the middle hinge of the joint.

The front arm *a* of the toggle is rotatably mounted on the breech block *k* and the rear arm *b* on the casing *g*. The breech block is inserted without play in the casing and the 40 front arm *a* of the joint is free of the breech block. The bearing or stops for the front hinge I of the joint and the rear hinge III are therefore fixed. The portion of the middle hinge of the joint which overlaps the 45 case bears snugly on its lateral walls (Fig. 2).

The gas pressure exerted in the direction of the axis of the bore on the bottom of the cartridge and through the latter on the 50 breech block *k* produces a resilient upward deformation of the casing between the hinge points I and III. Owing to this deformation the middle hinge II resting on the wall of the casing receives a blow from below 55 which causes the toggle to break. Owing to

the *vis viva* imparted to the toggle and to the breech block the latter then opens completely and in this operation cocks the closing spring (not shown). The wall of the casing is therefore here rendered operative 60 as the movable toggle stop and the opening of the toggle is produced even with the smallest angle of aperture merely by the upward deformation of the casing. The novel toggle breech permits of greater retardation of the opening movement and consequently more efficient action of the powder gases upon the projectile. Furthermore the opening movement is more uniform so that it is unnecessary to provide a separate breech 70 head for preventing the cartridge case from being torn off.

What I claim and desire to secure by Letters Patent of the United States is:—

1. Breech mechanism for automatic firearms with fixed barrel comprising a breech block, a breech casing, a spring influenced toggle joint connecting said breech block with said breech casing and adapted to hold said breech block in the closed position, said toggle joint being adapted to be broken by flexure of said breech casing due to the gas pressure. 75

2. Breech mechanism for automatic firearms with fixed barrel comprising a breech block, a breech casing, a spring influenced toggle joint connecting said breech block with said breech casing and adapted to hold said breech block in the closed position, said toggle joint bearing snugly against said breech casing in such a manner that it is forced upward by the flexure thereof due to the discharge of the firearm. 80

3. Breech mechanism for automatic firearms with fixed barrel comprising a breech block, a breech casing, a spring influenced toggle joint connecting said breech block with said breech casing and adapted to hold said breech block in the closed position, the middle hinge of said toggle joint bearing 90 snugly against said breech casing in such a manner that it is forced upward by the flexure thereof due to the discharge of the firearm. 100

In testimony whereof I affix my signature 105 in presence of two witnesses.

HUGO BORCHARDT.
